DESIGN FOR A PORTABLE LAMP

Everett Blake Huff, San Francisco, Calif.

Application November 29, 1947, Serial No. 142,886

Term of patent 7 years

(Cl. D48—20)

To all whom it may concern:

Be it known that I, Everett Blake Huff, a citizen of the United States of America and a resident of the city and county of San Francisco, State of California, have invented a new, original, and ornamental Design for a Portable Lamp, of which the following is a specification, reference is had to the accompanying drawings, in which:

I claim:

The ornamental design for a portable lamp, as shown.

EVERETT BLAKE HUFF.
